UNITED STATES PATENT OFFICE.

HOMER L. NIHELL, OF LOS ANGELES, CALIFORNIA.

SIGNAL.

Application filed February 10, 1926. Serial No. 87,258.

This invention relates to a direction signal for indicating a change in travel which is intended by the driver of a vehicle. More specifically, it appertains to a visual indicator which by its position signals the character of the change in travel contemplated, as for illustration, a right hand turn, a left hand turn, or a decrease in speed.

Devices such as movable arrows and hands operable by the vehicle driver have been satisfactorily employed as direction indicators. However, nearly all of such devices require mutilation, alteration of the vehicle body and permanent emplacement of the mechanism of the indicator. The present invention contemplates the provision of a device especially adapted to a closed motor car employing vertically slideable windows. The primary object of this invention is to provide a detachable unit indicator readily placed in position upon a vehicle and quickly removable therefrom, economical and simple in structure.

These objects together with other objects and corresponding accomplishments are obtained by means of the embodiment of my invention illustrated in the accompanying drawing, in which:

Fig. 1 is a vertical section through the supporting body showing a hand mounted thereon in elevation and means for operating the same; Fig. 2 is a plan view of the structure shown in Fig. 1; and Fig. 3 is a view of a fragment the front of a closed vehicle looking from the inside and showing my improved unit mounted in position for operation.

Referring more particularly to the drawings, I have shown the indicator as equipped with a hand for visually indicating the direction, although an arrow or any other device may be substituted therefor. The saddle or body comprises side walls 4 and 5 which are spaced a distance such that a pane 6 of glass may be snugly gripped thereby. Projecting from the lower end of inner leg or wall 5 is a ledge 7 having an aperture 8 at the center thereof and a slit 9 communicating therewith. It will be noted that the marginal edges of the slit 9 are inclined downwardly toward the hole 8, the circumferential edge of the hole being dished downwardly. This is best seen from an inspection of Fig. 1, and is for a purpose later

described. Outstanding from the wall 4 are brackets 10 forming a shoulder in which is pivotally mounted the arm 11 of a hand 12. A pivot pin 13 provides the mounting.

Extending transversely of the body is a guide 14. This guide may be formed of a tube mounted upon and secured to the top of the body or the body may be extended and the tube arranged to penetrate the body. It is obvious that the disposition of the tube is a matter of mechanical expediency. Secured to the arm 11 is a cord or line 15 which extends through the guide 14 and is provided on the other lead with beads or similar enlargements indicated by 16. These beads are of such size that they will readily pass through the opening 8. However the beads cannot pass through the slit 9.

Referring more particularly to Fig. 3, the inside of a closed body automobile is indicated with the window 6 at the side of the driver in half open position. The direction indicator unit is marked "A." It is mounted upon the window 6 by slipping the body over the top with the pane 6 in the slot, as shown best in Figs. 1 and 2. It is obvious that the inner faces of the walls 4 and 5 may be padded to prevent rattling and to provide a tight fit. The body is positioned with the hand on the outside of the pane and the line 15 with the beads on the inside. Normally the hand 12 is disposed with the arm hanging substantially vertically downwardly. This is in a position practically out of sight. Suppose it is desired to indicate that the driver is about to turn with the center of the turn on the side of the vehicle on which the indicator is mounted. The usual signal for such a turn is to project or hold the arm in a horizontal position, such as shown in Fig. 1. The hand may be placed in this position and held by pulling upon the cord 15 until the arm is horizontal.

In this position the middle bead or abutment will be located directly below the shelf 7. By pulling the string toward the closed end of slit 9, the bead will be disposed below the sides of the slit so as to bridge the latter. If the pull upon the cord is released, the bead will engage the ledge and the hand will be held in position. Due to the downward dishing of the sides of the slit, the latter will overhang the bead, and it will not slip from its position. Furthermore, when

the beads are being pulled downwardly to pass through the opening 8, if they engage the edges of the slit, they will slide downwardly toward the center of opening 8 and 5 pass through. If it is desired to make a turn in the opposite direction, the line 15 is pulled downwardly and the uppermost bead 16 disposed beneath the ledge. This causes the arm 11 and hand to be held in an upward and outward position which is the usual signal for a turn in that direction. If it is desired to indicate a stop or that the speed of the vehicle is to be slowed, the line is moved until the lowermost bead 16 is disposed directly beneath the ledge 7. In this 15 position, the hand and arm are directed at an inclination downwardly and outwardly. The beads 16 may be differently colored, in order to provide convenient markings where- 20 by it will be evident which bead should be located in engagement with the under side of the shelf for a given signal.

It is obvious that various mechanical changes may be made without departing 25 from the spirit of my invention. However, the broad inventive idea involves a unitary structure having the indicator and operating mechanism quickly detachable. In addition to the broader objects of this invention, 30 there are certain details of design, such as the construction whereby the unit straddles the pane.

What I claim is:

1. A direction indicator unit comprising a 35 body arranged to detachably straddle and rest upon an upright panel, a swingable visual indicator mounted on the outside wall of said body, a line passing over the top of said panel and to the inside wall thereof 40 and secured at the other end to said indicator, spaced abutments on said line, an outstanding member on the inside of said body having a way through which said line may pass but which said abutments will bridge 45 and thereby will hold said line and main-

tain said indicator in selected angular position.

2. A direction indicator unit comprising a body arranged to detachably straddle and rest upon an upright panel, a visual indicator pivotally mounted on the outside wall of said body, a line guide way extending transversely from the outside wall of said body to the inside wall thereof, a line passing through said guideway, spaced beads on said line, an outstanding ledge on the inside wall of said body having an opening and a slit communicating therewith through which said line may pass but which said beads will bridge and thereby hold said beads against the passage therethrough, said flexible line being connected to said indicator, said beads being located to engage the sides of said slit and hold said indicator in selected angular position.

3. A direction indicator unit comprising a saddle having spaced side walls arranged to detachably slip over and straddle an upright panel, a visual indicator pivotally 70 mounted on the outside wall of said body, a ledge outstanding from the inside wall of said body, a tubular guide passing transversely across said body, a line passing through said guide and secured at one end to said indicator whereby to swing the latter, spaced beads on said line, said ledge having an opening through which said beads and line may freely pass and a slit communicating therewith through which said line may freely pass but which said beads will bridge and thereby will hold the latter against passage therethrough, said beads being located to engage said ledge and hold said indicator in selected angular position.

In witness that I claim the foregoing I have hereunto subscribed my name this 3rd day of February, 1926.

HOMER L. NIHELL.
